SHOPPING BAG CARRIER

Daniel J. Coffey, New York, N. Y.

Application November 30, 1953, Serial No. 396,571

4 Claims. (Cl. 280—37)

This invention relates to shopping bags and more particularly to carriers therefor.

It is an object of the present invention to provide a shopping bag carrier adapted to support the base of the bag on rollers to permit the filled bag to be run along the supporting surface towards its destination without the necessity of having to lift the heavy bag off the ground.

It is another object of the present invention to provide a shopping bag and carrier therefor of the above type which may be conveniently carried in a large handbag type of container, the shopping bag being formed of knitted fabric which is foldable into a relatively small tube and the carrier being separable into two portions adapted to be compactly received within the bag.

It is still another object of the present invention to provide a carrier of the above type including separable parts which are easily and readily snapped together for operative use with a minimum of effort.

It is still another object of the present invention to provide a shopping bag carrier of the above type which is readily adapted to conventional heavy paper shopping bags.

It is still another object of the present invention to provide a luggage carrier which will rollably support the luggage bag and which includes novel means for releasably securing the carrier to the base of the leather bag.

Other objects of the present invention are to provide shopping bag carriers bearing the above objects in mind which are of simple construction, inexpensive to manufacture, have a minimum number of parts, are easy to use and efficient in operation.

For other objects and a better understanding of the invention, reference may be had to the following detailed description taken in connection with the accompanying drawings, in which:

Figure 1 is a perspective view of a shopping bag kit embodying the features of the present invention and showing the kit in a closed position ready for carrying;

Fig. 2 is an exploded perspective view of the parts comprising the present invention;

Fig. 3 is a longitudinal sectional view through the shopping bag and carrier when assembled for operative use;

Fig. 4 is a perspective view of a modified form of the present invention adapted to heavy paper shopping bags;

Fig. 5 is a longitudinal sectional view taken along the line 5—5 of Fig. 4;

Fig. 6 is a transverse sectional view taken along the line 6—6 of Fig. 5;

Fig. 7 is a vertical sectional view taken along the line 7—7 of Fig. 5;

Fig. 8 is an enlarged vertical sectional view showing the manner of securing the carrier portions together;

Fig. 9 is a fragmentary exploded perspective view of the portions making up the carrier.

Referring now to the figures, and more particularly to Figs. 1 through 3, there is shown a shopping kit embodying the features of the present invention and including a large handbag-like container 10 having a flat rigid base

2

11, handle straps 12 and 13, a cover flap 14 having an opening 15 through which is received a buckle 16 carried by the bag and retained therein by a strap 17 secured to the back of the bag, substantially as illustrated. During 5 carrying, the strap 12 will be looped over the strap 13 and the upper portion of the latter will be held in the hand with the strap 17 passing through buckle 16 to secure the cover in the closed position. To open the bag it is only necessary to remove the strap 17 from buckle 16, 10 as will be obvious. A hollow tube open at both ends 18 is provided and receives therein a rectangular bag 19 similar in shape to that of a conventional heavy paper shopping bag formed of knitted fabric so that the bag may be rolled up and inserted in the tube as shown in Fig. 2. The bag 19, however, is provided with a packet 20 formed by a layer of material 21 secured along its longitudinal edges to the bottom 22 of the bag 19 (Fig. 3). The bag 19 is provided with suitable carrying straps at each side at the upper edges thereof, not shown.

20 As a means of supporting the bottom of bag 19 when the latter is filled with groceries or the like and eliminating the necessity of lifting the same for transportation purposes, a first plate 23 is provided at one end with a pair of ball bearing casters 24 secured thereto by screws 25, 25 Fig. 2. The other end of the plate 23 is provided with an L-shaped slot 26 having an outwardly tapered side 27, the longitudinal sides of plate 23 at this end also being provided with the slots 28. A second plate 29 is integrally formed along each edge with upwardly extending 30 flanges 30 adapted to receive therewithin the slotted portion 28 of plate 23, the end of the plate 29 being integrally formed with an upwardly and horizontally bent portion 31 providing a three-sided pocket to receive the plate 23 and particularly the slotted portion 26 thereof.

35 The undersurface of plate 29 also has mounted thereon at the center thereof a ball bearing roller caster 32. The portion 31 is provided with an opening 33 aligned with the inner end of slot 26 and within which moves a depending pin or finger 34, carried at the inner end of a rotatable arm 34 having a fingered lug 35. The arm 34 is normally urged in a counter-clockwise direction by means of a spring intermediate horizontal portion 31 and plate 29, the lug 35 permitting the same to be rotated in a clockwise direction against the action of the spring, not 40 shown. Thus, when the slotted end of plate 23 is slid between flanges 30, the depending finger will ride along the inclined side 27 of slot 26 and be sprung into the laterally extending portion thereof whereby to secure the portions 23 and 29 together. To release the same, it is 45 only necessary to press the finger lug 35 to remove the depending finger from the inner end of slot 26 and to separate the plates. By this construction, the plate 23 may then be slid intermediate the bottom of bag 19 and the flap 21 whereupon the plate 29 may then be snapped 50 into place to provide a rollable support for the shopping bag 19 and to eliminate thereby the necessity of lifting the same from the ground when filled with groceries or the like, it being only necessary to pull or push the bag along the supporting surface. After the groceries have 55 been delivered, the finger lug 35 is pressed to permit the separation of plates 23 and 29 and their removal from the pocket 20 whereupon they are placed within bag 10 in the overlapping relation shown in dotted lines in Fig. 1. The shopping bag 19 is then folded up into a compact unit and disposed within the tube 18 and likewise disposed within the bag which may then be closed and carried in the usual manner.

60 Referring now particularly to Figs. 4 through 9, there is shown a modified form of the present invention wherein a heavy paper shopping bag 36 having a pair of handle portions 37 is provided at each end at the very bottom thereof with transverse slots 38 making a supporting

70

pocket from the bottom 39 of the bag. A carrier is provided and includes a plate 40 provided on the under surface on one end with ball bearing rollers 41 secured in place by screws 42, the other end of the plate 40 being provided with slots 43 (Fig. 9) and an inwardly extending slot 44 at the center thereof and a circular opening 45 adjacent the inner end thereof. A cooperating plate 46 is provided and includes an overlapped portion 47 and spacer strips 48, the inner edges of strips 48 being received in sliding engagement with the inner edges of slots 43 and abutting the ends thereof, the strips 48 being secured intermediate portions 46 and 47 by screws 49. A strip 50 (Fig. 8) is secured between portions 47 and 46 in longitudinal alignment with slot 44 and received therein when the plate 40 is slid between the strips 48. As a means of locking the plates 40 and 46 together, a member 51 having an upper curved surface pivotally mounts a plate 52 by means of a pin 53, the inner end of plate 52 carrying a detent 54 normally urged downwardly through opening 45 by means of a spring 55 housed in the other end of member 51 and in engagement with the outer end of plate 52. Thus, to assemble the plates, it is only necessary to press the outer end of plate 52 downwardly, slide plate 40 between plates 46 and 47 and permit the detent 54 to pass downwardly into opening 45. This assembly will, however, be done after the plate 40 has been inserted through the openings 38 in the bottom of bag 36, to provide a roller carriage therefor, as shown in Fig. 4. To disassemble, it is only necessary to press the plate 52 downwardly at the outer end and separate plates 40 and 46, removing the same from bag 36 which may then be folded up into a compact unit for portability, as can the plates of the carrier. A central roller 56 is provided below plate 46 and secured thereto by screws 57.

What is claimed is:

1. An article of the class described comprising the combination of a flexible shopping bag open at the top and provided therealong with gripping straps, a layer of material secured to the bottom of said flexible shopping bag along its longitudinal edges whereby to provide a pocket having openings at each end below the bottom of said bag, a first plate adapted to be slid intermediate the bottom of said bag and said layer of material from one end and through said openings, roller means provided on the bottom of said plate at one end, a second plate adapted to receive the free end of said first plate at the other end of said bag, roller means on the bottom of said second plate, and releasable means for securing said first and second plates together intermediate said layer of material and the bottom of said shopping bag.

2. An article according to claim 1, said releasable means for securing said plates together comprising said first plate at the free end thereof at each longitudinal side having an edge recess, said plate at said end at its central portion having a substantially L-shaped slot, said second plate being provided along opposite longitudinal edges

with upwardly extending flanges adapted to be received within said edge recesses, said second plate having an upwardly and horizontally bent plate portion providing a pocket adapted to receive the slotted end of said first plate therewithin, said upwardly and horizontally bent plate portion of said second plate having an opening aligned with the inner end of said L-shaped slot, and a rotatable arm having a depending finger provided on the top of said upwardly and horizontally bent portion to cooperate with the L-shaped slot, to secure said two plates together.

3. The combination with a shopping bag having lateral end openings at the bottom of each end of a first plate adapted to slide through one of said openings above the bottom of the paper bag, roller means provided on the undersurface of said first plate at the outer end thereof, a second plate adapted to pass through the other of said transverse openings and adapted to receive the other end of said first plate in snug relationship, roller means on the bottom of said second plate and releasable means for securing said first and second plates together within said openings.

4. The combination according to claim 5, said releasable means for securing said plates together comprising said first plate at its inner end at each side having an edge recess, said plate having a central longitudinal slot extending inwardly from the inner end thereof, a circular opening adjacent the inner end of said slot, said second plate having an upwardly and horizontally bent portion, spacer strips at each side of said second plate intermediate said second plate and said upwardly and horizontally bent portion adapted to be received within said edge recesses in said first plate, a longitudinal strip intermediate said second plate and its upwardly and horizontally bent portion thereof adapted to register with said inwardly extending slot in said first plate, a bracket on the upper surface of said upwardly and horizontally bent portion and having a curved upper surface, an arm pivotally mounted about said arcuate bracket for rocking movement, a detent fixedly carried at the inner end of said arm, said upwardly and horizontally bent portion having an opening aligned vertically with the circular opening in said first plate when said first plate is received intermediate said second plate, said upwardly and horizontally bent portion, and spring means carried by said bracket for normally urging said detent downwardly through said upwardly and horizontally bent and first plate openings.
